CLAIM

The ornamental design for a shoe as shown and described.

DESCRIPTION

FIG. 1 is a top perspective view of a shoe showing my new design;
 FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is an enlarged view of a portion labeled as "8" on FIG. 7; and,

FIG. 9 is an enlarged view of a portion labeled as "9" on FIG. 7.

The long dash-short dash broken lines depict enlargement boundaries that form no part of the claim. The evenly-spaced broken lines illustrate portions of the shoe that form no part of the claimed design.

1 Claim, 9 Drawing Sheets(56)
